UNITED STATES PATENT OFFICE.

HIDEO KOROMOGAWA, OF OKUBO, TOYOTAMA-GUN, JAPAN.

STONE-PLANING MACHINE.

Specification of Letters Patent. Patented Mar. 15, 1921.

1,371,311.

Application filed May 21, 1920. Serial No. 383,284.

To all whom it may concern:

Be it known that I, HIDEO KOROMOGAWA, subject of the Emperor of Japan, residing at No. 212 Hyakunin-machi, Okubo, Toyotama-gu, Tokyo prefecture, Japan, have invented certain new and useful Improvements in Stone-Planing Machines, of which the following is a specification.

This invention relates to improvements in stone planing machines and it is particularly devised to automatically plane a particular surface of a stone after the machine has been initially set.

The object of the invention is to provide a stone planing machine designed to support and move the stone beneath a revolving cutter rotating in a fixed plane, and to furnish mechanism for automatically shifting the stone so that one of its surfaces will be brought to a particular plane without manually controlling the machine after it has been originally set.

With the foregoing object outlined and with the other objects in view which will appear as the description proceeds, the invention consists in the novel features hereinafter described in detail, illustrated in the accompanying drawings and more particularly pointed out in the appended claims.

Referring to the drawings,

Figure 1 is a longitudinal sectional view of the machine. Fig. 2 is a bottom plan view of the same.

Fig. 3 is a transverse sectional view of the machine taken on line A B of Fig. 1.

Fig. 4 is a top plan view of the machine.

In the drawing "1" represents a frame which in the present instance is in the form of an inverted pan and mounted on the upper surface or table of the frame are a plurality of guide surfaces 2 having parallel V-shaped guiding grooves 2'.

The guiding surfaces 2 are spaced apart to provide a central space in which the stone carrying box 3 operates, and this stone box has its upper end open to receive a stone block 4. The bottom of the box 3 is provided with a plurality of supporting balls 6, which are mounted in semi-spherical casings 5, and the box 3 may be shifted longitudinally and transversely of the bed plate or table by riding on these balls.

Mounted on the guiding surfaces 2 and

2' are sliding plates 7 and 7' which are provided with depending V-shaped lugs which slide in the V-shaped grooves of the guiding surfaces.

The adjacent ends of the sliding plates are provided with transversely disposed bearings 8 in which are rotatably mounted threaded shafts 9 which engage nuts 10 secured to opposite sides of the stone carrying box 3.

From the foregoing description it will be understood that the sliding plates 7 and 7' are used to shift the stone carrying box 3 longitudinally of the machine and that the threaded shafts 9 are employed for shifting the stone-carrying box transversely of the machine.

The means for shifting the stone carrying box transversely will now be described. The shafts 9 are provided at their forward ends with fixed bevel gears 11 which at certain intervals, that is at the ends of the longitudinal movements of stone-carrying box, mesh with horizontally disposed bevel gears 12. These bevel gears 12 are fixed to vertical shafts which extend through the table of the frame and the lower ends of the shafts are provided with fixed ratchet wheels 13 and 13', the teeth of the ratchets being engaged by pawls 14 and 14' that are swiveled or pivoted on stud shafts 15 and 15' which depend from the under side of the table of the frame. The pawls are secured to the forward ends of levers 16 and 16' and the rear ends of the levers are designed to be intermittently engaged by trips 18 and 18' which are fixed to a longitudinally movable bar 17 that is slidably mounted in the lower portion of the frame 1. The left-hand end of the bar 17 is provided with a bifurcated belt shifter 19.

The table of the machine bed 1 is provided with a plurality of longitudinally disposed spaced vertical slots 20 in which are slidably mounted pins 21 and 21' which are fixed to the sliding plates 7 and 7' and these depending pins engage the levers 16 and 16' at the ends of the longitudinal strokes of the sliding plates 7 and 7' and cause said levers to strike trips 18 and 18' for the purpose of moving the belt shifter 19.

Mounted in the lower portion of the machine frame is a longitudinally disposed

horizontal rotatable shaft 25 which is provided with spaced screw threads for a purpose which will be hereinafter described.

Mounted on one end of the shaft is a free 5 pulley 22 and a fixed pulley 23, and surrounding the shaft and freely mounted thereon is a sleeve 28 carrying a fixed pulley 24. The threaded portions of the shaft 25 engage fixed nuts 26 and 26' carried by lugs 10 which depend from the sliding plates 7 and 7' and slide in longitudinally disposed alined slots 27 and 27' which are arranged in the bed of the machine frame.

When the belt shifter 19 is placed to connect the driving belt with the idle pulley 22 the machine will be inoperative, but when the belt shifter is moved to connect the belt with the pulley 23 the shaft 25 will be driven in one direction and this will cause 20 the threads of said shaft to operate in the nuts 26 and 26' and cause the sliding plates 7 and 7' together with the stone-carrying box 3 to be moved longitudinally of the machine in one direction. When the sliding 25 plates 7 and 7' approach the end of their stroke in this direction one of the pins 21 and 21' will strike its respective lever 16 or 16' and will cause one of the pawls 14 and 14' to turn one of the ratchets 13 and 13' 30 through a distance equal to the distance between two teeth of one of said ratchet wheels. At this time one of the gear wheels 11 is in mesh with one of the gears 12 and this will cause one of the gear-wheels 11 to 35 be turned slightly. The shafts of the gear wheels 11 are connected together by a crossed belt or chain 44 so that movement of one of said gears 11 will cause simultaneous movement of the other gear 11 in 40 the same direction, and simultaneous movement of the gears 11 will turn the shafts 9 and cause the threads of the same to move the nuts 10 and the stone-carrying box slightly transversely of the bed of the 45 machine frame.

For the purpose of moving the sliding plates 7 and 7' in the opposite direction the lever 16 or 16' which has been previously struck by one of the pins 21 or 21' will operate or engage one of the trips 18 or 18' to cause movement of the belt shifter 19 to bring the belt into engagement with the pulley 24. This pulley will operate through a sleeve 28 and gears 29, 30, 31, 32 and 33 55 to drive the shaft 25 in a direction opposite to its initial movement and in consequence the nuts 26 and 26' together with the sliding plates 7 and 7' and the stone-carrying box will be returned to their original position, this cycle will continue automatically until the stone 4 has been planed or dressed to the desired extent.

Located at the ends of the machine are bearing posts 35 and 35' which support a 60 horizontal longitudinally disposed rotary 65

shaft 36 which carries the planing cutter 34. This planing cutter is adapted to be fixed to the shaft 36 and to rotate in a fixed vertical plane and as the stone moves beneath the cutter said cutter will operate on the 70 upper surface of the stone to bring the same to the desired plane.

While I have shown and described the preferred embodiment of my invention, I am aware that various changes and modifications may be made in the construction 75 shown without departing from the spirit of the invention as set forth in the following claims.

What I claim and desire to secure by Letters Patent is:

1. A stone planing machine comprising a bed plate, a longitudinally and transversely movable stone-carrying support movably mounted on the upper surface of said bed 80 plate, a rotary cutter movable in a fixed plane and designed to operate upon a stone carried by said support, plates slidably mounted on said bed plate and provided with fixed nuts, a threaded shaft engaging 85 said nuts, means for rotating said shaft in opposite directions for moving said nuts and sliding plates in opposite directions, and means controlled by longitudinal movements of said bed plates for shifting the 90 stone-carrying support transversely of the bed plate.

2. A stone planing machine comprising a bed plate provided with a plurality of longitudinally disposed spaced guiding plates, a 100 plurality of spaced sliding plates mounted on said guiding plates, a stone-carrying support secured to said sliding plates and movable longitudinally and transversely of said bed plate, a stone cutter rotatable in a fixed 105 plane and designed to operate upon a stone carried by said support, means for simultaneously moving said sliding plates and said stone-carrying support longitudinally of the machine bed plate, and means controlled by longitudinal movements of said 110 stone-carrying support for shifting the stone-carrying support transversely to the bed plate.

3. A stone planing machine comprising a 115 bed plate provided with longitudinally disposed spaced guiding plates, sliding plates mounted on said guide plates and carrying rotatably mounted threaded shafts, a stone-carrying support provided with nuts which 120 engage said shafts, a stone cutter rotatable in a fixed plane and designed to operate on a stone carried by said stone support, members fixed to said sliding plates and provided with nuts, a second threaded shaft engaging the last named nuts, means for 125 rotating the second threaded shaft in opposite directions for moving the sliding plates and stone-carrying support longitudinal of the bed plate, and means controlled by longi- 130

tudinal movement of said stone-carrying support for causing simultaneous movements of the first named threaded shafts, for causing the stone-carrying support to be moved transversely of the bed plate.

5 4. A machine of the kind defined by claim 3 in which the guide plates and sliding plates are provided with coöperating grooves and projections for preventing 10 transverse movement of said sliding plates relatively to said guide plates.

5 5. A machine of the kind defined by claim 3 in which the first named threaded shafts are provided with fixed gears, gears mounted 15 on the bed plate and designed to be intermittently engaged by said gears, ratchets, fixably connected to the second named gears, pawls engaging said ratchets, levers pivotally connected to the bed plate and carrying 20 said pawls, pins fixed to the sliding plates and designed to intermittently engage said

levers, a sliding rod carried by the bed plate and having trips intermittently engaged by said levers, and a belt shifter controlled by movement of said sliding rod.

25

6. A machine of the kind defined by claim 3 in which the means for oppositely rotating the second named threaded shaft comprises a belt engaged pulley fixed to the second named threaded shaft, a sleeve loosely 30 mounted on the second named threaded shaft and provided with a pulley designed to be engaged with a belt, a gear fixed to said sleeve and a gear fixed to the second named threaded shaft, and gearing connecting the last named two gears.

In testimony whereof I affix my signature in the presence of two witnesses.
